PIPE CONSTRUCTION

Garnet Adam Maguire, St. John, New
Brunswick, CanadaApplication August 9, 1935, Serial No. 35,522
In Canada January 29, 1935

1 Claim. (Cl. 138—47)

This invention relates to pipe construction and more particularly to a type of construction which will facilitate the cutting of the pipe into suitable lengths or at desired points.

It has been usual to cut pipe, such as black and galvanized pipe, etc. with a cutting member employing a cutting disc, by screwing the cutter tightly against the pipe so that the disc bites into the surface of the pipe whereupon the cutter is rotated about the pipe preliminarily to make a groove. After the groove has been formed, oil may be placed in it for facilitating the cutting operation. This conventional method can be greatly improved upon since it presents considerable difficulty particularly in the case of a pipe which has a chilled surface which makes it quite difficult to force the cutting disc to penetrate the hard chilled surface so that it has to be forced against the pipe under considerable pressure. Moreover, it is not possible to make the first preliminary cuts in oil since, if oil is placed on the surface of the pipe, it would simply run off. Thus oil can only be applied after a preliminary groove has been cut.

It is therefore an object of the present invention to provide a new type of pipe structure which will permit preliminary cutting in oil and will obviate the necessity of applying heavy pressure on the cutting disc to force it to bite into the chilled surface of the pipe.

A further object of the invention is to provide a pipe structure which can be produced without any difficult and which will readily permit an easy oscillating movement of the cutter which will further facilitate the cutting operation.

A further object of the invention is to provide a pipe structure, any given length of which can be readily judged to determine immediately the point at which it is desired to mount the cutting tool.

With these and other objects in view the invention consists in providing a recess in the outer surface of the pipe positioned at predetermined points on the pipe, to receive the cutting disc of the pipe cutter and provide for a ready biting of the cutting disc into the uncut chilled surface and also permitting preliminary cuts in oil, the oil being held in the recess, as more fully described in the following specification and illustrated in the accompanying drawing which forms part of the same.

In the drawing:—

Figure 1 is a fragmentary perspective view of a piece of pipe, showing the recesses in its surface.

Figure 2 is a transverse section taken through

a piece of pipe at the point where a recess is formed, illustrating a pipe cutter mounted on the pipe with the cutting disc in the recess.

Figure 3 is an enlarged detail section taken transversely through a recess.

Referring more particularly to the drawing, 10 indicates a piece of pipe which according to the present invention is recessed as at 11, the recess being preferably V-shaped as shown in Figure 3 to coincide with the cutter, and of a suitable 10 length, preferably just slightly longer than the width of the average cutting disc. This will therefore permit a cutting disc 12, as shown in Figure 2, to enter into the recess and provide for sufficient play so that the cutter structure 13 15 can be oscillated backwards and forwards to provide for easy cutting of the pipe.

As shown in Figure 2 by the broken lines A and B, the cutter is oscillated back and forth from its central position approximately to these 20 lines until the cutting disc 12 has cut into the adjacent outer surface of the pipe whereupon the arc of movement of the cutter is widened until finally the cutter is completely rotated around the pipe forming a preliminary cut or groove of 25 the depth of the recess 11. The cutting disc 12 is brought into contact pipe under pressure by means of a suitable adjusting or tightening shank 14 and after the preliminary groove has been formed completely around the pipe, this shank is 30 turned to force the cutter further into the pipe and so on until the pipe is cut completely through, according to usual practice.

The recess 11 is preferably formed with straight end walls 15 preferably radially disposed with 35 respect to the pipe centre, so as to provide an edge into which the cutter will readily bite, and having regard to this formation and the fact that the cutter can be freely oscillated backwards and forwards so that it gains momentum with each 40 swing, it is readily apparent that the cutting operation is a comparatively simple one. Moreover, it is apparent that the cutting operation is further facilitated through the possibility of 45 using oil for the preliminary cutting, the recess providing in effect an oil well for the preliminary cutting of the hardened surface of the pipe. The recesses are preferably formed in the pipe surface in a given line and spaced apart a desired 50 distance but it is apparent that the recesses could be staggered if desired or placed in any other desired arrangement. The distance between each recess might be approximately two inches and if the length of pipe required did not coincide 55

with the position of one of the recesses the pipe could be cut at the nearest recess and a suitable fitting provided to make the connection where necessary.

- 5 By placing the recesses in the same area, that is, in a given line throughout the length of the pipe, the recesses can serve a further function which is extremely useful and that is to provide a direct indication as to the length of the pipe. In other words the recesses would serve in a similar manner to the markings on a yardstick and being spaced apart a definite distance they would readily indicate quite accurately the length 10 of the pipe or readily assist one in arriving at a given length to be cut from a long section of pipe. Of course certain of the recesses could be made a little longer than others, such as indicated at 16. For instance, the recess occurring 15 every six inches could be made longer so that one

could easily calculate the length of a given section of pipe immediately.

A further advantage of the recesses is that they are placed directly at right angles to the longitudinal axis of the pipe and consequently 5 the pipe may be cut off accurately at a right angle to the length, thus avoiding any possibility of a pipe length having an unevenly cut end.

What I claim as my invention is:—

As an article of manufacture, a pipe preformed 10 to facilitate cutting by a pipe cutter having a rotary cutting disc, said pipe being provided in its outer face with a short circumferential recess of substantial depth comprising a seat for receiving a cutter disc on initial placement of a cutter 15 tool, whereby on actuation of an engaged cutter tool the initial bite of its cutting disc occurs in a direction circumferentially of the pipe and while the disc is rotating.
